UNITED STATES PATENT OFFICE.

ALBERT H. TAYLOR, OF LIVERPOOL, ENGLAND, ASSIGNOR TO WESTERN DENTAL
MANUFACTURING COMPANY (1914) LIMITED, OF BRISTOL, ENGLAND.

ARTIFICIAL TOOTH.

1,134,965.

Specification of Letters Patent. Patented Apr. 6, 1915.

Application filed November 6, 1912. Serial No. 729,814.

To all whom it may concern:

Be it known that I, ALBERT HAMNETT TAYLOR, a subject of the King of England, residing at Clubmoor, Liverpool, in the 5 county of Lancaster, England, have invented a new and useful Improved Artificial Tooth, of which the following is a specification.

This invention has reference to artificial 10 teeth, and more particularly to the type called "pin mineral teeth", which are fastened, or adapted to be fastened in the plastic backing in which they are held; and the object and effect of the invention is primarily to provide an improvement in connection with such teeth by which the connection or fastening of the tooth to the frame or plate is generally more secure, and causes the resistance of the tooth to be 15 20 25 30 35 40 45 50 55 60 65 70 75 80 85 90 95

against the bite, so affording a great stability to the tooth.

According to this invention, the tooth has a projection on the back, the underside of which is cut to form a V shaped groove, 25 which extends in the case of an upper single tooth, from the lower outer edge of this projection; and above this projection, a single anchor pin is secured or cast in the tooth during its manufacture. The projection engages with the backing, and forms a secure fastening to the biting or active end of the tooth.

The invention is illustrated in the accompanying drawings, in which:—

35 Figure 1 shows a single-tooth fitted to a backing, the plate or frame being in section; Fig. 2, is a back view of the tooth; and Fig. 3 an under plan view of the tooth.

Referring now to the drawings, *a* is the 40 projection on the back of the tooth, showing the upwardly V shaped inclined or undercut recess between it and the body of the tooth; *b* is the single platinum or metal anchor pin; and *c* is the backing.

45 The projection *a* which is a part of the tooth, overhangs or projects beyond the lower part of the back of the tooth. The

invention is not restricted to this particular form of construction of the back of the tooth, as it will be varied to suit different requirements.

The projection *a* as shown in Fig. 2, is so shaped that the center portion of it is slightly lower than the side portions; and the sides of the tooth are curved or rounded inwardly toward the back, as seen in Fig. 3. Owing to the curved or rounded sides of the tooth, the commencement of the projection *a* occurs at points a little distance within the extreme edges of the sides as shown. This enables teeth to be well fitted, and to be set closely to one another.

The invention is especially useful in connection with the front or single upper teeth, as it is these teeth, that are, in most cases, 65 pressed outward by the lower teeth in biting food, as the upper edges of the lower teeth come under the lower or biting edges of the upper teeth, and press them outward. A tooth of the construction and form herein 70 described, can be so firmly and securely fixed or set in the backing that abnormal pressure is necessary to press it out or break it away from the backing. Further the teeth cannot be loosened during the biting action, 75 that is, when the lower teeth strike the lower and inner surface of the upper teeth, the pressing outward of the upper teeth is opposed by the projection *a* which is formed on each tooth and is securely held in the 80 backing by reason of the recess beneath each of the projections being occupied by a part of the backing, and the under inclined surface of each projection being more or less at right angles to the line of action tending to 85 push the tooth from the backing, such pushing action being exerted by the lower teeth in the biting action. The whole setting and fastening of the teeth in the backing is exceptionally firm, and generally improved.

90 By the improved construction, one of the two platinum pins usually required, is dispensed with, and thereby considerable reduction in the cost of the teeth is obtained.

What is claimed is:—

In an artificial tooth, the combination of a biting edge, an overhanging portion, a rear surface extending from the biting edge for a part of the length, an undercut V-shaped recess formed by the projection and rear surface and a single headed pin baked in the tooth substantially as described.

In testimony whereof I have signed my name to this specification in the presence of 10 two subscribing witnesses.

ALBERT H. TAYLOR.
